UNITED STATES PATENT OFFICE.

HAROLD J. BELL, OF GLOUCESTER CITY, NEW JERSEY, ASSIGNOR TO THE WELSBACH INCANDESCENT GAS LIGHT COMPANY, OF NEW JERSEY.

GAS-PRESSURE REGULATOR.

SPECIFICATION forming part of Letters Patent No. 417,136, dated December 10, 1889.

Application filed June 6, 1889. Serial No. 313,328. (No model.)

To all whom it may concern:

Be it known that I, HAROLD J. BELL, a citizen of the United States, residing at Gloucester City, in the county of Camden and State of 5 New Jersey, have invented new and useful Improvements in Gas-Pressure Regulators, of which the following is a specification.

My invention relates to that class of gas-pressure regulators in which the varying pressure of gas delivered to the regulating apparatus is controlled and made uniform by the action of the gas on a flexible rising-and-falling diaphragm with which the regulating-valves are connected.

15 The invention consists in the construction and combination of parts as hereinafter set forth, with reference to the annexed drawing, which represents a vertical section of a gas-pressure regulator embodying my improvements.

Referring to the drawing, the numeral 1 designates a casing provided with a detachable cover 2, having a vent-pipe 3 connected to its top. In the upper part of this casing, 25 between its body and cover, is secured a flexible diaphragm 4, composed of rubber, leather, or other suitable material. This diaphragm 4 is provided with a central rigid portion 5, having a central opening, in which is secured 30 the upper externally-screw-threaded end of a depending partly tubular stem 6, to the upper end of which is attached an internally-threaded cap 7, by which said diaphragm and stem are connected. The cap 7 and the connected tubular end of the stem 6 form a vertically-elongated valve-chamber 8, having an outlet-opening 9 in its upper end and an inlet-opening 10 in its lower end. The inlet-opening 10 communicates with an open-ended 40 passage 11, formed transversely through the stem 6 beneath the diaphragm. In the valve-chamber 8 is loosely placed an elongated vertically-movable valve-plug 12, which forms, with said chamber, an automatic safety relief- 45 valve for protecting the flexible diaphragm 4 from the injurious effects of excessive pressure.

In one side of the casing 1, below the diaphragm, is an outlet-opening 13 for the attachment of a gas-delivery pipe, and in the

opposite side of the casing is an opening in which a gas-inlet pipe 14 is inserted. On the inner end of the gas-inlet pipe 14, within the casing 1, is a valve-casing 15, which is provided at top and bottom with vertically-elongated gas-passages 16 and 17, that communicate directly with the interior of the regulator-casing. The gas-inlet pipe 14 is secured by a nut 18 on its outer externally-threaded portion, and is provided within the casing 1 55 with a depending flange or arm 19, through which is passed one end of a screw-bolt 20, that is engaged with the casing-wall, thereby preventing the pipe 14 and attached valve-seat chamber 15 from turning.

To the lower end of the diaphragm-stem 6 is pivoted one end of a lever 21, the other end of which is fulcrumed in a knife-edged opening or slot 22, that is formed in the flange or arm 19 of the gas-inlet pipe. This lever 21 is 60 pivotally connected to a lug or lugs 23 on the lower part or end of a vertical valve-stem 24, that carries the regulating-valves 25 and 26, and which valve-stem is preferably formed in 65 separable parts, as shown. The elongated valve-seat gas-passages 16 and 17 form guide-ways for feathers or wing-guides 27, that are formed on the valve-stem 24 at or near its ends. As shown, the valves 25 and 26 consist of annular disks preferably composed of 70 elastic or flexible material that will readily seat in a true and proper manner on the ends of the annular flanges 16 and 17, that form the gas-passages of the valve-casing. The valve-stem 24 is formed in separable parts connected 75 by screw-bolts 28, carried by one part and engaging threaded recesses in the adjoining part. On the adjoining parts of the valve-stem are flanges 29, between which the flexible or elastic valve-disks 25 and 26 are received. It will be observed that the upper valve 25 is located in the valve-casing 15, between the gas-passages 16 and 17, while the lower valve 26 is outside said chamber and beneath the lower gas-passage 17, leading 80 therefrom. The upper end of the gas-passage 17 is formed into a valve-seat for the valve 25 to seat downward upon, and on said upper valve-seat, in connection with the valve-seat 85 30 of the gas-passage 17, constitute what I 90

term a "duplex valve-seat" at the lower-end portion of the valve-casing 15.

Gas admitted to the apparatus through the upper passage 16 accumulates beneath the flexible diaphragm 4 and exerts a pressure thereon whereby it is lifted, so as to actuate the lever 21 and carry the valves 25 and 26 upward into position to permit the flow of gas through both passages 16 and 17 at normal pressure. Should the pressure become excessive, the valves 25 and 26 will be elevated still farther and carried nearly or quite into contact with the depending valve-seats 30, where they will remain momentarily until the pressure beneath the diaphragm is relieved, so as to permit the valves to lower. In this way the rise and fall of the flexible diaphragm acting through the stem 6 and lever 21 on the vertically-movable regulating-valves 25 and 26 will automatically and constantly control the pressure of gas delivered by the apparatus.

What I claim as my invention is—
A gas-pressure regulator consisting of an

outer casing comprising a gas-chamber containing a flexible diaphragm and having a 25 gas-inlet and a gas-outlet, a valve-chamber located within the gas-chamber, opening at its upper and lower ends directly into the latter beneath the diaphragm, and provided at its lower end portion with a duplex valve-seat 30 and in its upper end portion with an internal depending valve-seat, a valve-stem having two valves both of which close at different times on the lower duplex valve-seat and one of which closes upwardly against the internal 35 valve-seat, and a lever supported at one end below the valve-casing, connected at its other end with the diaphragm-stem and between its ends sustaining the valve-stem, substantially as described.

In testimony whereof I have affixed my signature in presence of two witnesses.
